UNITED STATES PATENT OFFICE.

GEORGE W. BLACKBURN, OF COLUMBUS, OHIO.

DISH-CLEANER.

SPECIFICATION forming part of Letters Patent No. 555,671, dated March 3, 1896.

Application filed August 26, 1895. Serial No. 560,465. (No model.)

To all whom it may concern:

Be it known that I, GEORGE W. BLACKBURN, a citizen of the United States, residing at Columbus, in the county of Franklin and State 5 of Ohio, have invented a certain new and useful Improvement in Dish-Washers, of which the following is a specification.

My invention relates to the improvement of dish-washing machines; and the objects of 10 my invention are to provide an improved dish-washer of simple and reliable construction by means of which dishes, knives, forks, spoons and other similar articles may be quickly and thoroughly washed, and to produce other improvements which will be more 15 specifically pointed out hereinafter. These objects I accomplish in the manner illustrated in the accompanying drawings, in which—

Figure 1 is a side elevation of my improved 20 washing device. Fig. 2 is a plan view showing one of the half-lids raised, and Fig. 3 is an enlarged sectional view on line xx of Fig. 1.

Similar letters refer to similar parts throughout the several views.

25 In the construction of my improved dish-washer I employ a substantially bucket-shaped body or casing a , preferably of sheet metal, said body being provided with a suitable bail-handle, as indicated at a' . On opposite 30 sides of the upper portion of the casing a I provide vertical sockets b , the latter being adapted to receive the downturned or vertical end portions of a bridge-bar b' , which extends across the body a above the center 35 thereof. To the center of the bottom of the casing a is secured the lower end of a spirally-grooved pin or rod c , the latter extending upward preferably to about the height of the casing a . Passing downward loosely through 40 the bridge-bar b' is a tubular stem c' , the lower end portion of which is adapted to fit, as shown, within a short vertical and central socket-piece d , which rises from the floor of a washing case or basket d' . The tubular 45 stem c' is, as shown, adapted to fit loosely about the grooved rod c , while the lower portion of said stem is surrounded by said washing-case, which is of such circumference as to result in the formation of a slight space 50 between its periphery and the wall of the casing a . The washing case or basket has its sides and bottom perforated, as indicated at d^2 .

From the central socket-piece d of the washing-case radiate the desired number of grooved wings or blades e , the lower sides of 55 the latter being secured to the bottom of said basket. Through corresponding threaded openings formed in said socket-piece d and in the lower portion of the tubular stem c' passes a threaded pin e , said pin being thus 60 adapted to connect the washing-basket and tube c' and to project within the spiral groove of the rod c .

The upper end of the tube c' is provided with a crank-handle f . As indicated in the 65 drawings, the upper side of the casing a is adapted to be closed by two half-disk-shaped lids g , which are hinged respectively to opposite sides of the casing-top, the inner and straight edges of said lids being provided with 70 central recesses h to insure their fitting about the stem c' .

The manner of utilizing my improved dish-washer consists in first arranging the dishes or other articles to be washed within the basket d' and between the blades e thereof, then 75 filling or partially filling the casing a with hot water and imparting a rotary or reciprocating movement to the stem c' .

Owing to the fact that the pin e is projected 80 into the spiral groove of the rod c , it is obvious that turning the handle f will not only result in a rotation of the stem c' and basket d' , but that said basket will travel up and down within the casing a , the pin e filling the spiral 85 groove of the rod c . In this manner it will be observed that the combined rotary and vertical movement of the washing-case will be had within the water which is contained in the casing a , and that the dishes and other 90 articles contained in said basket will thus be subjected to the desired frictional and washing contact with the water.

It is evident that by so turning the handle f as to raise the dish-supporting basket above 95 the water said basket may be retained in a desirable position for draining the dishes contained therein.

Having now fully described my invention, what I claim, and desire to secure by Letters 100 Patent, is—

1. In a dish-washing device the combination with the casing a and a vertical spirally-grooved rod therein, of a washing-basket sur-

rounding said rod, a pin projecting from said washing-basket into the spiral groove of said rod and means for rotating said basket, substantially as and for the purpose specified.

- 5 2. In a dish-washing device the combination with the casing *a*, a spirally-grooved rod extending upward from the bottom of said casing and a detachable bridge-bearing bar supported from and above the same, of a wash-
10 ing case or basket within said casing *a* and about said rod *c*, a tubular stem *c'* passing

loosely through the bridge-bar *b'* and adapted to incase the grooved rod *c*, a pin *e* connecting said washing-basket and tubular stem and projecting within the groove of the rod *c* and means for rotating said stem *c'* substantially as and for the purpose specified. 15

GEORGE W. BLACKBURN.

In presence of—
DAVID MILLER,
R. C. DICKERSON.
